(57) CLAIM

The ornamental design for a clear container with magnifying feature, as shown and described.

DESCRIPTION

FIG. 1, is a perspective view of the clear container with magnifying feature showing my new design;

FIG. 2, is a front elevational view thereof;

FIG. 3, is a rear elevational view thereof;

FIG. 4, is a side elevational view, the undisclosed opposite side being a mirror image thereto;

FIG. 5, is a top plan view thereof;

FIG. 6, is a bottom plan view thereof;

FIG. 7 is a front elevational view of FIG. 1 with the addition of unclaimed indicia and environment being shown in broken lines; and,

FIG. 8 is a rear elevational view of FIG. 1 with the addition of unclaimed indicia and environment being shown in broken lines.

Portions of the design and the indicia are shown in broken lines for illustrative purposes only and form no part of the claimed design.

1 Claim, 6 Drawing Sheets
